ELECTRIC BLOCK SIGNALING SYSTEM

APPLICATION FILED 8EPT 20 1902

7 SHEETS—SHEET 3.

<img alt="A detailed technical electrical circuit diagram, likely a patent drawing, showing a complex network of wires, components, and labels. The diagram includes a large rectangular box on the right containing a switch, two light bulbs labeled 'RED' and 'GREEN', and several numbered terminals (91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 2061, 2062, 2063, 2064, 2065, 2066, 2067, 2068, 2069, 2069, 2070, 2071, 2072, 2073, 2074, 2075, 2076, 2077, 2078, 2079, 2079, 2080, 2081, 2082, 2083, 2084, 2085, 2086, 2087, 2088, 2089, 2089, 2090, 2091, 2092, 2093, 2094, 2095, 2096, 2097, 2098, 2099, 2099, 2100, 2101, 2102, 2103, 2104, 2105, 2106, 2107, 2108, 2109, 2109, 2110, 2111, 2112, 2113, 2114, JOHN W. DAVIS, OF LOS ANGELES, CALIFORNIA, ASSIGNOR TO MILLS-PIDDINGTON CAB SIGNAL COMPANY, OF LOS ANGELES, CALIFORNIA, A CORPORATION OF CALIFORNIA.

ELECTRIC BLOCK-SIGNALING SYSTEM.

No. 897,355.

Specification of Letters Patent.

Patented Sept. 1, 1908.

Application filed September 20, 1907. Serial No. 388,840.

To all whom it may concern:

Be it known that I, JOHN W. DAVIS, a citizen of the United States, residing at Los Angeles, in the county of Los Angeles and State of California, have invented new and useful Improvements in Electric Block-Signaling Systems, of which the following is a specification.

This invention relates to an electric block signaling system. The system may be used in connection with steam, electric, or other railways and whether the latter involves one or two tracks. The system is simple in its nature and the various parts are effective and quick in their action.

In the drawings accompanying and forming part of this specification I illustrate in detail certain forms of embodiment of the invention which, to enable those skilled in the art to practice the same, will be set forth at length in the following description, while the novelty of the invention will be included in the claims succeeding said description.

Referring to said drawings: Figure 1 is a diagram of the system used in connection with a single track. Fig. 2 is a like view of the same when employed in connection with a double track. Fig. 3 is a similar view showing the single track wiring and connections with a station. Fig. 4 is a front elevation and Fig. 5 a side elevation of the vehicle or engine relay. Figs. 6 and 7 are top and bottom plan views of the same. Fig. 8 is a side elevation of a portion of the engine, track rail, and contact rail. Fig. 9 is a like view of the track rail and contact rail. Fig. 10 is a detail view in end elevation and cross section of a portion of a locomotive track, contact rail, and brush. Figs. 11 and 12 are sectional details of track relay devices viewed from right-angles to each other. Figs. 13 and 14 are, respectively, sectional bottom plan and top plan views of said track relay devices.

Like characters refer to like parts throughout the several figures.

I will first describe in detail the system shown in Fig. 1; certain of the parts represented in said figure are shown also in Figs. 4 to 7 and 11 to 14, inclusive. In said Fig. 1 I have shown two rails 2 and 3 over which vehicles as 4 and 5 are adapted to travel. The rails 2 and 3 are utilized as conducting means, the rail 3 being divided into sections 55 or blocks by means of suitable insulation as

situated between the ends of the sections. The blocks or sections may be of any desirable length. The vehicles 4 and 5 may be of any character; for instance, a locomotive or an electric car. When the system is used in connection with a steam railway it is my preference to mount certain of the signals in the cab of the locomotive or engine, and these signals may be of any suitable character; for example, a red signal can be used to indicate danger, while a green signal can be utilized to show safety, and I prefer also when the red signal shows to simultaneously put into action an audible signal such as a bell. The red and green signals may consist of incandescent lamps.

At intervals along the rails, either between or outside the same as preference may dictate or particular conditions require, I place sets of contact rails as 7 and 8, the contact rails 7 being in proximity to the rail 2, while the contact rails 8 are adjacent to the rail 3. The contact rails 7, therefore, are operative with a vehicle as 4 when the same is traveling toward the right in Fig. 1, while the contact rails 8 are operative with the vehicle 5 when the same is traveling toward the left in said figure. These contact rails 7 and 8 may be of any desirable length, they ordinarily being thirty feet and they are separated suitable distances apart. Their working portions are preferably placed above the surface of the track rails, as clearly shown in Figs. 8 and 9, and their terminals are down-turned, bent, or curved so as to facilitate the entrance there onto and departure therefrom of contact members as 9 and 10 on the forward trucks of the cab 4. These contact members may be wheels suitably insulated from the framework of the locomotive or they may consist of brushes as 9' and 10', as indicated in Figs. 8 and 10.

I will now describe in detail the connections on one of the locomotives, such as the locomotive 4, and this will apply to the other as these connections are of duplicate character. From the contact wheel 9 a wire 11 leads and from said wire 11 to the locomotive battery 12 there is extended a wire 13. Said wire 13 is connected with one pole of said battery 12, while from the other pole thereof the wire 14 is extended and leads to the coils of the main electro-magnet or engine relay 15. From the said engine relay

or electro-magnet 15 a wire 16 is extended and is connected electrically with the locomotive, for example, with the front axle of the front truck thereof. The armature for the main magnet or relay 15 is denoted by 17 and it is electrically connected with the wire 14. The magnet or relay 15 is suitably mounted in the cab of the locomotive or engine and its frame pivotally supports 10 said armature 17. When the armature 17 is against the contact 18 the red lamp will be lighted, and the same result follows when the armature is against the contact 19, all as will hereinafter appear. There 15 is connected with the armature 17, see for example Figs. 4 and 5, an arm 20 provided at its free end with an armature 21 for the locking magnet 22. The armature sweeps across the pole of the locking magnet 22. 20 The latter is normally energized being in a local circuit, as will hereinafter appear, so as to normally maintain the armature 17 in one of its several relations. When the two contact wheels 9 and 10 are on a contact rail 7 the locking magnet 22 is short circuited, the result being that the same is deenergized, so that at this time the armature 17 can be freed to effect the setting of a signal. The free end of the armature is 25 adapted to engage the free end of the spring-arm 23 attached to the framing of said magnet 15, as indicated in said Figs. 4 and 5, the resiliency of said spring contact arm 23 being sufficient to normally maintain it 30 against the contact point 24. When a track circuit hereinafter described is closed there will not be power enough in the circuit, owing to the fact that resistance is interposed therein, to energize the magnet 35 15 sufficiently to cause its armature 17 to overcome the effect of the spring contact arm 23, the result being that during this condition the contact arm 23 will remain against the contact 24. Should, however, 40 the track circuit be broken, the magnet 15 will be deenergized so that the armature 17 can drop against the contact 18 to cause the flashing of the red lamp through connections hereinafter described. On the 45 other hand, should the said track circuit be shorted, resistance will be cut out, and such a condition will prevail that an excessive amount of current can be supplied to the magnet 15 to energize the same sufficiently to overcome the tension of the 50 spring arm 23 and to permit the armature 17 to engage the contact 19, at which time the red lamp will be flashed. From the contact 55 19 the wire 25 leads to one terminal of the red lamp 26, a wire 27 leading from the other terminal of said red lamp to one terminal of the green lamp 28. From the 60 other terminal of said green lamp to the contact 24 there is extended a wire 29. 65 The wire 11 previously described is con-

nected with the wire 27 and is intersected by the wire 30 which leads to one terminal of the bell 31, while the wire 32 leads from the other terminal of said bell to the wire 25, said wire 32 being intersected by the wire 33 which extends to the contact 18. From the wire 11 to one terminal of the magnet 22 the wire 34 extends, the wire 35 extending from the other terminal of said magnet 22 to the contact wheel 10. From the wire 35 to the wire 11 a wire 36 extends, said wire 36 being intersected by the battery 37. It will be understood that I use certain of the terms herein in their generic senses, and where I use such a designation as "battery" I intend to cover other forms of generators.

By virtue of the connections described it will be evident that the locking magnet 22 is normally energized so as to hold the signal in a desired relation. The circuit for the locking magnet involves a battery 37, wire 36, part of wire 11, and wire 34. When both contact wheels 9 and 10 are upon a contact rail 7 the locking magnet 22 is short circuited so as to permit the proper action of the armature 17 for the setting of a signal. When both wheels 9 and 10 are on such a rail 7 the current from the battery 37 traverses the wire 36, wire 11, wheel 9, contact rail 7, wheel 10, wire 35, wire 36, to battery 37 for cutting out the locking relay 22.

The armature 17 in Fig. 1 is in contact with the spring arm 23 and the latter in turn is against the contact 24. In such a relation as this a green light will be displayed as follows: From the battery 12 current will flow to the wire 14, armature 17, arm 23, contact 24, wire 29, to lamp 28, wire 27, wire 11, wire 13 to battery. This is the normal relation of the parts. Should a train be within a prescribed distance of the locomotive 4 the track circuit, as will hereinafter appear, will be broken, thereby deenergizing the magnet 15 and permitting its armature 17 to drop against the contact point 18. In such a condition as this the red lamp 26 will be flashed, current passing from the battery 12 to the wire 14, armature 17, contact 18, wire 33, wire 32, lamp 26, wire 27, wire 11, wire 13 to battery 12. By virtue of the connection of the bell 31 with the wires 11 and 33 the bell will be sounded when the armature 17 is on the contact 18. The red lamp and bell will be also rendered effective when the armature 17 is on the contact 19, and, in this case the current will flow from the battery 12 to the wire 14, armature 17, contact 19, wire 25, lamp 26, wire 27, wire 11, and wire 13 to battery. The last named condition may be due to various causes, for example, by the electrical bridging of a contact rail 7 and adjacent rail 2, such as by a piece of metal which may be a coupling pin or something of like character.

I will now describe in detail the connections utilized for indicating to an engineer in one engine when another engine is in the same block that the first engine occupies, and these connections are repeated throughout the system.

For illustration I will denote the conductor rail on the lower side of Fig. 1 nearest the locomotive by the character 7^a. From this conductor rail 7^a a conductor 40 extends and leads to the contact point 41 co-operative with which is the gravity armature 42 of the track relay 43. From this armature 42 the wire 44 extends and to the contact point 45 co-operative with which is the armature 46 of the track relay or magnet 47. From the armature to the rail 2 a wire 48 extends, and said wire is intersected by the resistance 49. I have just described a local track circuit. The battery 50 connected with the two rails 2 and 3 serves to energize the relay 43, while the battery 51 performs a like function with respect to the relay 47. The wires 44 are generally laid in pairs along one side of the track and they may be strung on poles. I prefer also to mount two of the relays as 43 and 43^a upon a common support, as shown clearly in Figs. 11 to 14, inclusive. In like manner the relays 47 and 47^a may be mounted upon a common support.

It will be assumed that neither of the locomotives or engines 4 and 5 is shown in the drawings. In such a case as this the armature 42 will be against the contact point 41 and the armature 46 will be against the contact point 45. Normally, therefore, the several track relays are energized so as to attract their armatures to make a succession of local circuits along the track. It will be assumed that the conditions shown in Fig. 1 exist. In such an event a red signal will be flashed in the cab of the locomotive 4 when the brushes or contact wheels 9 and 10 travel on the contact rail 7^a. The two green signals shown in Fig. 1 are both set and the locomotive 5 has approached sufficiently near to the battery 51 as to deenergize the relay 47 so as to break the circuit between the tip of the armature 46 and the contact point 45. When the wheels 9 and 10 enter upon the contact rail 7^a the magnet 22 will be instantly deenergized for the purpose of permitting the setting of a signal, and as soon as the wheel 10 passes off the contact rail 7^a the said magnet 22 will be energized to retain the signal thus set in the manner fully previously described. When, therefore, the wheels 9 and 10 are on the contact rail 7^a and when the armature 46 has fallen away from the contact point 45 a red signal in the cab 4 will be shown owing to the fact, as will herein-after be obvious, that the engine relay or magnet 15 is cut out thereby permitting the armature 17 to drop against the contact 18 and causing the red signal to flash in the man-

ner previously described. Of course, if the engine 5 is not within the range of the battery 51 the current from the latter will energize the magnet or relay 47 for the purpose of flashing a green lamp to indicate safety, and in this case the current will flow from the battery 12, wire 13, wire 11, contact wheels 9 and 10, contact rail 7^a, wire 40, contact 41, armature 42, wire 44, contact 45, armature 46, wire 48, rail 2, frame of engine 4, wire 16, magnet or relay 15, and wire 14 to battery. The current traverses the resistance 49 so that its strength is so reduced that the magnet 15 when energized has not sufficient power to overcome the resistance of the spring arm 23, the result being that the latter remains on the contact 24 and the green signal shows. It will be understood that exactly similar conditions occur on the engine 5.

A contact rail such as 7^a and the adjacent rail 2 are sometimes electrically bridged, and, in such a case as this, the engineer will have notice of the difficulty, and I provide a means whereby, when such a contingency as this arises, the danger signal will be set. Should this accident occur the current will pass from the battery 12 to wire 14, magnet 15, wire 16, frame of locomotive, rail 2, contact rail 7^a, contact wheels 10 and 9, wire 11, wire 13, to battery 12. There is no resistance in this circuit so that the full strength of the current from the battery 12 can be given to the magnet 15, the result being that the armature 17 is drawn firmly against the poles of said magnet and against the contact point 19, the resistance offered by the spring 23 to the movement of said armature being overcome by the maximum strength of the current. I have described hereinbefore the flow of the current through a circuit involving the armature 17 and contact 19, for which reason the same need not be here repeated.

Referring now particularly to Fig. 2 I have shown the system as adapted to double tracks, the rails of the respective tracks being denoted by 2' and 3' respectively. These rails are divided into sections at suitable intervals by insulating joints such as previously set forth. The two locomotives are designated by 4' and 5' and their connections are exactly as has been hereinbefore described in detail in connection with Fig. 1, for which reason it is needless to describe again these features in conjunction with Fig. 2. The blocks in Fig. 2 may be of any desirable length, for example, three-quarters of a mile, and there is shown in said Fig. 2 three complete blocks which, for convenience, will be designated by 60, 61, and 62. At the entrance of each of these blocks is positioned a polarized track relay as 63 and at the other end of said block is placed a battery as 64 controlled by a polarized relay such as that referred to and denoted by 63. Referring to

said Fig. 2 it will be seen that the engine 5' is in the block 60. This short circuits the relay 63^a, cutting off the current by the battery 64, and allowing the neutralized armature 65^a 5 and the polarized armature 66^a to drop, thus reversing current from battery 64^b in block 61. By reversing the current in block 61 the polarized armature 66^b is permitted to drop. The neutral armature 65^b, however, is retained in its upper position. It will be seen 10 that all neutral armatures of track relays have double contact points which are connected to the respective track batteries. These contact points work between upper 15 and lower contact points, the upper ones in each case being denoted by 67 and the lower ones by 68, by virtue of which I can reverse the current in the blocks. With each neutral armature is also connected a contact 69 20 adapted to engage the coöperating polarized armature 66. I desire to explain at this point that, although there are several relays 63, armatures 65, and armatures 66, I have given for convenience of description some of 25 these parts exponents or further distinguishing characters to facilitate the understanding of the invention.

Between the armatures 66 and track rails 2' are wires 69 intersected by resistance coils 30 as 70. I have described in detail certain local track circuits which are repeated throughout the double track system through each track thereof. It will be assumed that the engines 4' and 5' are in the relation set 35 forth. In this event the local circuit including the armature 66 is broken by the dropping of said armature in the manner described, the break being between the armature 66^b and the contact point 69. When, therefore, 40 the contact wheels or brushes of the locomotive 4' travel on to the contact rail 7^a near which they are shown the magnet 15 will be deenergized as previously fully described permitting its armature to drop to 45 display the red signal and ring the bell, all as also fully described. Should the engine 5' be not in the block 60 the armature 66^b will be against the point 69 thereby making a local circuit involving the contact rail 7^a so that, 50 when the wheels or brushes 9 and 10 of the locomotive 4' are on said contact rail 7^a, the green lamp circuit will be completed in the engine, the current from the battery 12 traversing the resistance coil 70. Should the 55 contact rail 7^a and adjacent rail 2' be bridged electrically as hereinbefore set forth, the full strength of the battery current 12 can be supplied to the magnet 15 so as to attract its armature 17 against the point 19 to display 60 the danger or red signal and also to ring the bell.

It will be understood that the several contact rails 7^a have electrical connection with the contact points 71 coöperative with the 65 armatures 65, that the magnets 63 are elec-

trically connected with the rails 2' and 3, respectively, that the contact points 67 are also connected with said rails 2' and 3', and that the contacts 68 are also connected with said rails 2' and 3', whereby there are formed 70 a succession of local circuits, one circuit having means for controlling an adjacent circuit.

In Fig. 3 I have shown the single track equipment of Fig. 1 and a station equipment I will apply to the track connections in Fig. 3 75 the same characters which I have adopted in describing Fig. 1, although in some cases to make the description clear I will adapt modifying exponents for these characters. The wiring of the station in said Fig. 3 is 80 practically the same as the engine wiring, although to make the description explicit I deem it desirable to employ different characters for the station wiring. The wiring is of duplicate character, so that, if I describe 85 one side of the station equipment, this will apply to the other, although the battery 71' is common to both sides. From the battery 71' a wire 72 extends to the switch contact point 73, the switch being designated by 74 90 and being normally upon the contact 75 from which the wire 76 leads, said wire 76 being connected with the wire 77 which at one end is connected with the wire 78 connected with adjacent terminals of the two signal lamps. 95 From the red signal lamp the wire 78 extends to the contact 79. From the green signal lamp the wire 80 extends to the contact 81 with which is coöperative the spring contact arm 82, the exact equivalent of the 100 arm 23 hereinbefore described. This spring contact arm coöperates with the armature 83 of the magnet 84 to which the wire 77 extends. The wire 77 leads to one pole of the magnet 84, while the wire 85 leads from the 105 other pole thereof and to the contact rail 7^a. From said contact rail 7^a the wire 40 leads as previously described. The wire 72 leads from one pole of the battery 71', while from the other pole thereof the wire 71^a extends, 110 said wire 71^a being in turn connected with the wire 71^b electrically connected with the rail 2'. When, therefore, the receiving switch 74 is against the two contacts 73 and 75 and when the armature 46 is away from the contact 45 due to the presence of the locomotive at the point 86, the armature 46 will drop, thereby breaking the local circuit involving said armature 46 at a point between the latter and the contact 45 so that 115 the armature 83 can drop against the contact 79 to flash the red lamp in the manner previously described. Should the armature 46 be against the contact 45 and the receiving switch be in the position pointed out the 120 green lamp will be flashed, assuming, of course, that the locomotive is not at the point marked 86, the battery next the locomotive when at the point 86 being adapted to hold the armature 46 against the contact 125 130

45, the current from the battery 71' at this time traversing the resistance 49 so that the strength of the battery 71' is not sufficient to cause the armature 83 to overcome the 5 effect of the spring arm 82. From the wire 78 there extends a wire 87 to the contact 88 so that, should the contact rail 7^a be electrically connected through some accident with the rail 2', the full current from the 10 battery 71' will traverse the coils of the magnet 84 so that the armature 83 is drawn to the poles of said magnet overcoming the pressure of the spring arm 82 and carrying said armature 83 against the contact 88 for 15 flashing the red lamp. The signal bell is denoted by 89 and it intersects a wire 90 connecting the wires 77 and 78, by reason of which, when the red lamp flashes, the bell will also ring.

20 The signaling switch is shown at 91 and this co-operates with the contact points 92 and 93. From the contact point 93 to the main rail 3' a wire 94 extends. From the contact point 92 a wire 95 extends and leads 25 to the wire 71^a which is connected with the track rail 2' by means of the wire 71^b. If, therefore, the signaling switch 91 be upon the contacts 92 and 93 the magnet 43^a can be short circuited so as to show a red signal 30 in the cab of the locomotive occupying the position 86 in said Fig. 3.

What I claim is:

1. The combination of railway rails at least one of which is in insulated sections, 35 contact rails co-operative with said railway rails, a source of electrical energy connected to each insulated section of said railway rails, magnets within and electrically connected with each insulated section of said railway 40 rails, armatures for the magnets, a contact point for one of the armatures, electrically connected to one of said contact rails, the other armature being connected through a resistance with one of the railway rails, and a contact 45 engageable by the second armature and electrically connected with the first armature of the magnets in the preceding insulated section of railway rails.

2. The combination of railway rails at 50 least one of which is in insulated sections, contact rails co-operative with said railway rails, means for supplying current to the railway rails, magnets within and electrically connected with each insulated section of said 55 railway rails, armatures for the magnets, a contact point for one of the armatures, electrically connected with one of said contact rails, the other armature being connected through a resistance with one of the railway 60 rails, a contact engageable by the second armature and electrically connected with the first armature of the magnets in the preceding insulated section of railway rails, and a vehicle to travel along said railway rails, having 65 current collecting means to engage said

contact rails and also having signals of different character electrically connected with said current collection means.

3. The combination of railway rails at least one of which is in insulated sections, 70 contact rails co-operative with said railway rails, means for supplying current to the railway rails, magnets electrically connected with each insulated section of said railway rails, armatures for the magnets, a contact 75 point for one of the armatures, electrically connected with one of said contact rails, the other armature being connected through a resistance with one of the railway rails, a contact engageable by the second armature and 80 electrically connected with the first armature of the magnets in the preceding insulated section of railway rails, and a vehicle to travel along said railway rails, having current collecting means to engage said contact 85 rails and also having different colored lamps electrically connected with said current collecting means.

4. The combination of railway rails at least one of which is in insulated sections, 90 contact rails co-operative with said railway rails, a source of electrical energy connected with said railway rails, magnets within each insulated section of railway rails and electrically connected with said railway rails, armatures for said magnets, a contact point for 95 one of the armatures electrically connected to one of said contact rails, the other armature being connected through a resistance with one of said railway rails, and a contact 100 engageable by the second armature and electrically connected with the first armature of the magnets in the preceding insulated section of railway rails.

5. The combination of a magnet, a contact, a lamp connected with said contact, a second contact, a second lamp connected with said second contact, a third contact connected with the first lamp, an armature for said magnet, an automatically-operable device normally against said second contact and adapted to resist the movement of said armature toward its magnet, and means for energizing the magnet and supplying the 105 lamps with current.

6. The combination of a magnet, a contact, a lamp connected with said contact, a second contact, a second lamp connected with the second contact, a third contact connected with the first lamp, an armature for 110 said magnet, a spring arm normally against the second contact and adapted to engage the armature and to resist the movement of the same toward its magnet, and means for energizing the magnet and supplying the 115 lamps with current.

7. The combination of a magnet, a contact, a lamp connected with said contact, a second contact, a second lamp connected with the second contact, a third contact con- 120

125
130

nected with the first lamp, an armature for said magnet, a spring arm normally against the second contact and adapted to engage the armature and to resist the movement of 5 the same toward its magnet, means for energizing the magnet and supplying the lamps with current, and a switch for cutting the lamps in and out.

8. The combination of a vehicle, a magnet 10 on the vehicle, a contact, a lamp connected with said contact, a second contact, a second lamp connected with the second contact, a third contact connected with the first lamp, an armature for said magnet, a spring arm 15 normally against the second contact and serving to resist the movement of the armature toward its magnet, and means for energizing the magnet and for supplying current to the lamps.

20 9. The combination of a vehicle, a magnet on the vehicle, a contact, a lamp connected with said contact, a second contact, a second lamp connected with the second contact, a third contact connected with the first lamp, 25 an armature for said magnet, a spring arm normally against the second contact and serving to resist the movement of the armature toward its magnet, means for energizing the magnet and for supplying current to the 30 lamps, and a locking magnet provided with an armature coöperative with the first armature.

10. The combination of a vehicle having contact members, a magnet on the vehicle, a 35 contact, a lamp connected with said contact, a second contact, a second lamp connected with the second contact, a third contact connected with the first lamp, an armature for said magnet, a spring arm normally against 40 the second contact and adapted to engage the armature to resist the movement of the same toward its magnet, an electrical con-

nexion between one terminal of the magnet and the vehicle, an electrical connection between the other terminal of the magnet and one of said contact members and involving a battery, a magnet, the armature of which is coöperative with the first mentioned armature, an electrical connection between the other contact member and said locking magnet, and a battery for the locking magnet.

11. The combination of a vehicle having contact members, a magnet on the vehicle, a contact, a lamp connected with said contact, a second contact, a second lamp connected with the second contact, a third contact connected with the first lamp, an armature for said magnet, a spring arm normally against the second contact and adapted to engage the armature to resist the movement of the same toward its magnet, an electrical connection between one terminal of the magnet and the vehicle, an electrical connection between the other terminal of the magnet and one of said contact members and involving a battery, a magnet, the armature of which is coöperative with the first mentioned armature, an electrical connection between the other contact member and said locking magnet, a battery for the locking magnet, railway rails along which the vehicle travels, and a local circuit associated with the railway rails and involving a contact rail adapted to be engaged by said contact members and also involving an automatically operative circuit controller and a resistance.

In testimony whereof I have hereunto set my hand in presence of two subscribing witnesses.

JOHN W. DAVIS.
